(57) **CLAIM**

The ornamental design for a foldable portable wall-mounted height measuring device to measure the height of a person, and a stamped recordation of the date the height measurement was taken, as shown and described.

DESCRIPTION

FIG. 1 is a front perspective view of the foldable portable wall-mounted height measuring device to measure the height of a person, and a stamped recordation of the date the height measurement was taken, showing my new design;

FIG. 2 is a rear perspective view thereof;

FIG. 3 is front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
